*Primary Examiner—Lucy Lieberman***[57] CLAIM**

The ornamental design for a stackable container, as shown and described.

DESCRIPTION

FIG. 1 is a perspective view of a stackable container, showing my new design;

FIG. 2 is a cross-sectional view thereof;

FIG. 3 is a perspective view showing many thereof;

FIG. 4 is a perspective view showing a second embodiment of FIG. 1;

FIG. 5 is a cross-sectional view thereof; and,

FIG. 6 is a perspective view showing many thereof.

The portions of the stackable container that are not shown in the drawings do not form part of the claimed design.

The broken lines in the drawings are for illustrative purposes only, and do not form part of the claimed design.
